UNITED STATES PATENT OFFICE

ENID TAYLOR, OF NEW YORK, N. Y.

DESIGN FOR A COMBINED TRAY AND RECEPTACLES FOR TOILET PREPARATIONS

Application filed March 31, 1931. Serial No. 39,309. Term of patent 7 years.

To all whom it may concern:

Be it known that I, ENID TAYLOR, a citizen of Great Britain, residing at New York, in the county and State of New York, have invented a new, original, and ornamental Design for a Combined Tray and Receptacles for Toilet Preparations, of which the following is a specification, reference being had to the accompanying drawing, forming part thereof, and in which drawing—

Fig. 1 is a side elevation of a combined tray, and receptacles for toilet preparations, which receptacles remain intact as parts of the holder;

Fig. 2 is a longitudinal section in part;

Fig. 3 is a plan view.

I claim:

The ornamental design for a combined tray and receptacles for toilet preparations, substantially as shown and described.

ENID TAYLOR.
